UNITED STATES PATENT OFFICE.

ALBERT L. NEW, OF LOS ANGELES, AND WILLIAM N. HICKMAN, OF AVALON, CALIFORNIA;
SAID HICKMAN ASSIGNEE OF ONE-HALF OF HIS RIGHT TO SAID NEW.

COMBINATION SENDING AND RECEIVING WIRELESS-TELEGRAPH APPARATUS.

No. 876,281.

Specification of Letters Patent.

Patented Jan. 7, 1908.

Application filed September 17, 1906. Serial No. 335,013.

To all whom it may concern:

Be it known that we, ALBERT L. NEW and WILLIAM N. HICKMAN, both citizens of the United States, the former residing at Los Angeles, in the county of Los Angeles and State of California, and the latter residing at Avalon, Santa Catalina Island, county of Los Angeles, and State of California, have invented new and useful Improvements in Combination Sending and Receiving Wireless-Telegraph Apparatus, of which the following is a specification.

This invention relates to wireless telegraphy and the main object of the invention is to provide a system wherein each station is equipped for sending and receiving.

A further object is to provide means for preventing interference of the apparatus by atmospheric electricity.

Another object is to provide a double set of aerial capacities one of which is adapted for sending and the other for receiving.

Another object is to provide means to reduce any disturbance or distant signal to a very mild or low sound, and yet admit any other signal desired so that it will be heard distinctly and read regardless of the subdued signals.

Another object is to permit the reception of the nearby weak signals and exclude strong signals from a distant point.

Other objects and advantages will appear from the following description.

The accompanying drawings illustrate the invention and referring thereto:—the figure is a diagrammatic view illustrating one form of apparatus.

1 designates a mast with a cross arm 2 from one end of which is supported a set of sending wires 3 forming a transmitting capacity. From the other side of the cross arm is supported a receiving capacity comprising a set of wires 4. A cross arm 5 supports conical cups 6 which insulate the lower ends of the wires 3 and 4 from the ground. A wire 7 leads from the upper ends of the wires 4 directly to ground, and is provided with an induction coil 8 so that signals from stations at a considerable distance will come through the atmosphere distinct and readable.

Connected to the sending aerial capacity 3 is a transmitting apparatus comprising a spark coil 9 having vibrator 9^a from the primary of which spark coil a wire 10 extends to an alternator 11. A wire 11^a ex-

tends from the other lead of the primary to an adjusting device 12, which comprises a tube 13 formed of insulating material around which is wound a wire 14 in several layers. Slidably adjustable in the tube 13 is a soft iron core 15 which is adjustable therein by means of a rack 16 operated by a pinion 17. The wire 11^a is connected to one end of the wire 14. The other end of the wire 14 is connected by a wire 18 with a double-throw 65 three pole switch 19. The alternator 11 is connected by a wire 20 with a switch 19. A mile-meter 21 is connected with wires 10 and 20. This mile-meter is constructed similarly to a volt-meter and by adjusting 70 the core 15 to fill the tube 13 the hand of the mile-meter will indicate the lowest distance in miles to which the sending apparatus is adjusted, and by withdrawing the core 15 the hand of the mile-meter will indicate the 75 maximum distance to which the apparatus is adjusted for the transmission of a signal which when received at the end of said distance will be of a definite strength. Adjusting for intermediate distances being accomplished by regulation of the core.

The induction coil 9 is of the usual construction, one pole of its secondary being connected with ground by wire 22 in which is connected a condenser 23, the other pole 85 of the secondary is connected by a wire 24 with the sending wires 3. A key 25 is provided in the wire 18 and the sending apparatus is adjusted as follows. If the signal is to be sent to a station 50 miles distant the 90 operator closes the key 25 and by turning the pinion 17 adjusts the core 15 until the hand of the mile-meter 21 stands in a position indicating 50 miles; the apparatus being adjusted for other distances in like manner. A wire 26 extends from the receiving wires 4 to the switch 19, and a wire 27 leads from the switch 19 to ground. A wire 28 leads from switch 19 to a rheostat 29 and a condenser 30 which is connected in the wire 100 28 may be cut out when desired by the shunt circuit 31 which is equipped with a switch 32. From the rheostat 29 a wire 33 extends to a receiving instrument comprising a microphone indicated at 34, and from 105 the microphone a wire 35 leads to a rheostat 36, and a wire 37 leads from rheostat 36 to a double throw switch 38 having terminals 39 and 40. A wire 41 leads from terminal 39 to the receiving instrument 34 and is con- 110

nected with the battery 42. A wire 43 leads from terminal 40 to the receiving instrument 34, the wire 43 being connected with a battery 44 which is of about one-half 5 the strength of battery 42. Telephone receivers 45 are connected in the wire 35.

In receiving the switch 19 is moved so that it makes contact with the upper terminals only, and when the signal is received 10 it comes in over a circuit which may be traced as follows: from the receiving capacity 4 through wire 26 to switch 19, through wire 28 to rheostat 29 and through wire 33 to receiver 34 then through wire 35 and wire 15 46 to switch 19, thence through wire 27 to ground. With the switch 38 in contact with terminal 39 the local circuit through the receiver is as follows: from battery 42 and through wire 41 to receiver then through 20 wire 35 to rheostat 36, and through wire 37 to switch 38 and then to battery 42. By throwing switch 38 into contact with terminal 40 the local circuit through the receiver will operate over the branch 43 containing the 25 smaller battery. When the switch 19 is in this position the primary circuit through the sending apparatus is open so that while the operator is receiving no signal can be made with the key to disturb the receiving apparatus. When the switch is thrown to make 30 contact with its bottom terminal the primary circuit is closed so that signals can be made with the key 25, but as the entire regulating, receiving, and switch instruments are entirely 35 disconnected from ground and mast wires, they may be at any distance from the sending set, and therefore no induction or great power can come into the office or to the receiving table to shock the operator. The 40 operator can signal back and forth and exchange telegrams without leaving his table, by means of the three pole double throw switch 19, being able to change instantly from sending to receiving, and vice versa, 45 without having to call the other office and without danger. We have operated this with 100 volts primary power and about 200,000 volts induced power from induction coil without any interference or danger and 50 it is believed that interference and danger will be eliminated when using unlimited power.

When two signals (a weak one and a strong one) come in on the receiving mast 55 set, resistance is cut in at 29 until the wave length is decreased for both a sufficient degree, this being determined by listening at the phones 45 with only battery 44 cut in. When sufficiently reduced the switch 38 is 60 thrown to heavy battery 42 which causes microphone receiver 34 to become deadened or cohered; then the resistance at 36 is gradually cut in until the battery is reduced to a point such that there will still be enough 65 resistance or decoherence in the microphone

to allow the weaker signal to be heard, while the signal of larger volume escapes to ground through the coherence of the microphone on account of insufficient resistance at the microphone to divert the current of the signal to the phones. 70

What we claim is:—

1. A plurality of aerial capacities insulated from each other, a transmitting apparatus in circuit with one of said capacities, a receiving 75 apparatus in circuit with the other capacity, means for varying the strength of the impulse produced by the transmitting apparatus, means electrically connected with the transmitting circuit for indicating in miles 80 the effective radius of an impulse with definite strength, a plurality of ground connections, and means for switching one of said ground connections to the transmitting circuit or another ground connection to the receiving circuit. 85

2. A plurality of aerial capacities insulated from each other, a transmitting apparatus in circuit with one of said capacities, a receiving apparatus in circuit with the other capacity, 90 means for varying the strength of the impulse produced by the transmitting apparatus, means electrically connected with the transmitting circuit for indicating in miles the effective radius of an impulse with definite strength, a plurality of ground connections, means for switching one of said ground connections to the transmitting circuit or another ground connection to the receiving circuit, a variable resistance in the receiving 95 circuit, a local branch circuit embracing a receiving device connected with the receiving circuit, a variable resistance in the local circuit, a battery of definite strength in said local circuit, and a shunt in said local circuit 100 with a battery of less strength, and a switch for cutting in said shunt. 105

3. A plurality of aerial capacities insulated from each other, a transmitting apparatus in circuit with one of said capacities, a receiving 110 apparatus in circuit with the other capacity, means for varying the strength of the impulse produced by the transmitting apparatus, means electrically connected with the transmitting circuit for indicating in miles 115 the effective radius of an impulse with definite strength, a plurality of ground connections, means for switching one of said ground connections to the transmitting circuit or another ground connection to the receiving circuit, a variable resistance in the receiving 120 circuit, a local branch circuit embracing a receiving device connected with the receiving circuit, a variable resistance in the local circuit, a battery of definite strength in said 125 local circuit, and a shunt in said local circuit with a battery of less strength, and a switch for cutting in said shunt, a wire extending directly from the receiving aerial capacity to ground, and an inductance coil therein. 130

4. A plurality of aerial capacities insulated from each other, a transmitting apparatus in circuit with one capacity, a receiving apparatus in circuit with the other capacity, variable resistance in the receiving circuit, a local circuit embracing a receiving device in the receiving circuit, a variable resistance in said local circuit, a shunt in said local circuit with a battery, a battery in said local circuit, one of said batteries being of greater power than the other, and a switch for cutting in said shunt circuit, a plurality of ground connections, and means for connecting one ground connection with the receiving circuit or for connecting another ground connection with the transmitting circuit. 30
5. A plurality of aerial capacities insulated from each other, a transmitting apparatus in circuit with one capacity a receiving apparatus in circuit with the other capacity, variable resistance in the receiving circuit, a local circuit embracing a receiving device in the receiving circuit, a variable resistance in said local circuit, a condenser in said receiving circuit, and a shunt for cutting out said condenser, a plurality of ground connections, 35
- 10
- 15
- 20
- 25
- 40
- 45
- and a switch for connecting one ground connection with the transmitting circuit or another ground connection with the receiving circuit. 30
6. A plurality of aerial capacities insulated from each other, a single support therefor, a transmitting apparatus in circuit with one of said capacities, a receiving apparatus in circuit with the other capacity, means for varying the strength of the impulse produced by the transmitting apparatus, means electrically connected with the transmitting circuit for indicating in miles the effective radius of an impulse with definite strength, a plurality of ground connections, and means for switching one ground connection to the transmitting apparatus or another ground connection to the receiving circuit. 35
- In testimony whereof, we have hereunto set our hands at Avalon, Calif. this 1st day of September 1906.
